UNITED STATES PATENT OFFICE.

ERASTUS WOODWARD AND MATTHIAS BROCK, OF BOSTON, MASSACHUSETTS, ASSIGNORS TO THE COPELAND LASTING MACHINE COMPANY, OF HARTFORD, CONNECTICUT.

MEANS FOR SUSPENDING POWER PEGGING-MACHINES.

SPECIFICATION forming part of Letters Patent No. 227,944, dated May 25, 1880.

Application filed March 29, 1880. (Model.)

To all whom it may concern:

Be it known that we, ERASTUS WOODWARD and MATTHIAS BROCK, both of Boston, in the county of Suffolk and Commonwealth of Massachusetts, have invented an Improvement in Means for Suspending Power Pegging-Machines, of which the following is a specification.

This invention is an improvement upon the mechanism for suspending a power pegging-machine described in our Letters Patent of the United States filed on the 22d day of April, 1879, and dated August 5, 1879.

It consists in a modification in the construction of the mechanism, whereby the power pegging-machine may be provided with additional adjustments by the substitution of a gimbal-joint for the swinging hanger and swiveling supporting-rod of the said patent.

Reference is made to the accompanying drawings in explaining the nature of our invention, in which—

Figure 1 is an end elevation of the gimbal-joint and connecting-rod, with the counterbalanced tilting bar for supporting the pegging-machine shown in dotted outline. Fig. 2 is a plan of the gimbal-joint, showing its construction. Fig. 3 is a vertical central section, and Fig. 4 is a view, part in elevation and part in section.

The mechanism described in said patent for suspending the pegging-machine allows it to be moved in all directions in relation to the surface of the work or any other fixed point; but the swiveling connection for providing it with lateral movement at right angles to the line of the counter-shaft does not allow the machine to be moved as readily and as quickly as is desirable, and it does not provide for so great a range for the movement of the pegging-machine in such a direction, the machine for the purposes of said adjustment being swung on a center corresponding to that of the axis of the vertical suspending-rod.

The gimbal-joint provides means for the movement of the pegging-machine in all directions from the center of the driving-pulley on the counter-shaft.

In the drawings, A represents the counter-shaft, provided with suitable bearings in the hanger or hangers a or other suitable support; B, the driving-pulley; C, an open frame, forming a portion of the gimbal-joint, supported at the point c by the counter-shaft A, and provided with the pivots c' at right angles to the axis of the shaft, which support the hanger c^2 , forming a portion of the gimbal-joint, and from which the rod c^3 , which holds the tilting rod c^4 in the same manner that the rod s^6 holds the rod s' in the patent referred to, depends. The said rod c^3 preferably should be arranged to swivel in the hanger c^2 .

The frame C, it will be observed, entirely surrounds the driving-pulley.

The advantages of this construction over that described in our said patent do not need to be further enumerated.

The belt c^5 practically supports the counterbalanced tilting bar, and the bar c^3 serves to steady and stay it.

Having thus fully described our invention, we claim and desire to secure by Letters Patent of the United States—

As a means for suspending power pegging-machines, the combination of the tilting frame C, having the pivotal bearings c upon the shaft A, and surrounding the pulley B, the converging hangers c^2 , pivoted at c' to the frame C, and the rod c^3 , suspended by said hangers beneath the pulley and supporting the tilting counterbalanced pegging-machine supporting-bar c^4 , substantially as described.

ERASTUS WOODWARD.
MATTHIAS BROCK.
